F. J. CASSARETTO

DIRECTION SIGNAL FOR VEHICLES

Filed April 27, 1925

INVENTOR

Frederick J. Cassaretto

BY *George W. Winter*
ATTORNEY

UNITED STATES PATENT OFFICE.

FREDERICK J. CASSARETTO, OF STOCKTON, CALIFORNIA.

DIRECTION SIGNAL FOR VEHICLES.

Application filed April 27, 1925. Serial No. 26,057.

To all whom it may concern:

Be it known that I, FREDERICK J. CASSARETTO, a citizen of the United States, residing at Stockton, county of San Joaquin, 5 State of California, have invented certain new and useful Improvements in Direction Signals for Vehicles; and I do declare the following to be a full, clear, and exact description of the same, reference being had 10 to the accompanying drawings, and to the characters of reference marked thereon, which form a part of this application.

This invention relates to improvements in vehicle direction signals of that type 15 which includes an arm adapted to be moved to assume different positions corresponding to the positions assumed by the human arm when the latter is used for signaling purposes. Such devices are of course intended 20 to take the place of the human arm, and are located on the vehicle where the signal arm can be readily seen by others.

The principal object of my invention is 25 to provide a signal of this character having novel features of construction and operation, and one especially adapted for installation on motor vehicles of the sedan or other closed body types.

A further object of the invention is to 30 provide control means for the signal so arranged that it may be selectively moved to different positions by hand, and it will also be automatically moved to one only of said 35 positions when the foot brake of the vehicle is applied; the hand or selective and automatic operations not interfering with each other.

A further object of the invention is to 40 produce a simple and inexpensive device and yet one which will be exceedingly effective for the purpose for which it is designed.

These objects I accomplish by means of 45 such structure and relative arrangement of parts as will fully appear by a perusal of the following specification and claims.

In the drawings similar characters of reference indicate corresponding parts in the several views:

Fig. 1 is a perspective view of my signal 50 showing the same mounted in the frame work of a closed car body.

Fig. 2 is a rear view of the signal and the hand operating means therefor, the adjacent face of the signal casing being removed.

Fig. 3 is a fragmentary side view of the 55 upper portion of the signal member.

Fig. 4 is a sectional diagram showing the connection between the hand signal control member and the foot brake rod.

Fig. 5 is a fragmentary transverse section 60 of the signal, on the line 5—5 of Fig. 3.

Fig. 6 is a fragmentary perspective view of the signal arm detached.

Referring now more particularly to the characters of reference on the drawings, the 65 numeral 1 denotes a vertical rectangular casing, open along its outer face and adapted to be set into the front side post 2 of a car body so as to be preferably flush therewith and with the open side of the casing facing to 70 the side of the car.

Fixed in the casing adjacent the upper end thereof is a shaft 3 on which is turnably mounted a head 4. Fitting onto the outer end of the head is a hollow signal arm 5, 75 preferably rectangular in section and of suitable length. This arm is of frosted glass or other translucent material and is of such dimensions that when vertically disposed it will fit inside the casing and be thus protected from damage.

Secured at the outer end of the head and projecting into the signal arm is an electric light bulb 6 backed by a suitable reflector 7. The signal arm is removably mounted on the 85 head so as to be easily detached to replace the bulb when necessary by means of metal T members 8. Suitable grooves 9 are cut in the arm and head to receive these members, which are so disposed that their cross heads 90 are set in the arm, while their stems extend beyond the arm and over the head 4 for a certain distance. The stems are removably attached to the head by screws 10. Thus it will be seen that when the members 8 are in 95 place the arm is held from longitudinal displacement on the head 4, but may be immediately slipped off when said members are removed.

A hollow drum 11 is fixed on one end of 100 the head 4, on which drum is wound a cable 12 or the like which extends to the bottom of the casing and then out through the back of the casing around an ordinary direction changing sheave 13. To enclose the drum 105 and the cable a vertical partition 14 is mounted in the casing from top to bottom thereof and located between the head 4 and

the drum. Therefore while that part of the casing in which the arm is located may be left open to the outside the other side may be completely enclosed so as to protect the drum and cable from dirt, dust and the elements generally.

A spiral spring 15 is housed in the drum, one end of the spring being attached to the drum and the other to the fixed shaft 3, and 10 arranged so that the arm 5 is normally held in a vertical position or concealed in the casing. It will therefore be seen that if the cable is pulled down, the drum will be rotated and the arm swung upwardly from its 15 concealed or vertical position.

According to the laws of this State a signal extending at a downward 45° angle indicates "stop"; a horizontal position of the signal denotes "left turn"; and an upward 20 45° angle of the signal denotes "right turn". To enable the signal to be readily moved to these different positions I provide the following operating and control means.

Mounted on the dashboard 16 of the vehicle 25 at a suitable location is a plate 17 having a vertical slot 18. Slidable in the slot is a stem 19 having on its outer end a knob or handle 20. The cable 12 is connected to the inner end of the stem leading to said 30 stem over a sheave 21 which is located a certain distance to one side of the sheave 13. The sheave 21 is also located to one side of the vertical plane of the slot 18 thereabove, so that the cable from the stem to said sheave 35 extends at an upward angle to the slot. The slot has spaced recesses 22 to partially receive the stem, said recesses being located on that side of the slot toward which the cable slants. The recesses are disposed so that 40 when the stem is seated therein the signal arm is moved to the left turn and right turn signaling positions.

By reason of the recesses and the slope of the cable, the stem is automatically pulled 45 sideways into said recesses when the stem is horizontally aligned therewith. The operator may then let go of the knob and then said knob will remain set until the operator moves the stem laterally out of the recess by 50 manipulation of the knob. The spring 15 will then act to restore the arm to its neutral or concealed position in the casing.

A positioning of the stem intermediate the top of the slot and the first recesses will place 55 the signal arm in a stop signal position. A recess for such position may also be provided but I preferably omit the same for reasons hereinafter seen.

Since an intention to stop is almost always 60 accompanied by a brake application I operatively connect the stem to the brake rod 23 so as to move the stem and signal to the stop position upon the depression of the brake pedal 24 by the following means.

65 An additional length of cable 25 extends

downwardly from the stem to the rod 23 over any necessary number of direction changing sheaves 26, so arranged that when the rod moves forward with the application of the brakes, the stem 19 will be moved down- 70

To insure that the stem will only be moved the distance necessary to move the signal to a stop position regardless of the extent of movement of the brake rod, I provide a stop member 27 on the cable 25 adapted to abut 75 against a fixed member of the car when the cable has been moved the required distance. To then allow of further movement of the brake rod without breaking the cable, I interpose a tension spring 28 therein between 80 the stop 27 and rod 23.

In this manner it will be seen that whenever the brake pedal is depressed the signal arm will be automatically moved to its stop indicating position and will return to a neutral position as soon as the brake is released, and without hand manipulation of the knob 20 by the operator being necessary, owing to the omission of a stop-position recess in the slot 18. At the same time it will be seen that 90 the signal may be set to any position by hand without interfering with the brake control mechanism and regardless of whether the brakes are set or not, since with such hand manipulation the cable 25 merely becomes 95 slack.

In this signal device the lamp 6 is intended to be lit continuously just as are the running lights and it is wired in the lighting circuit without any additional switch means 100 being necessary. This is possible, because with my arrangement the arm when not extended is concealed from view ahead or behind the vehicle and consequently cannot give a false signal.

If the device is used for open cars, the casing would of course be provided with a suitable bracket or clamps for attachment to the windshield or the like.

From the foregoing description it will be 110 readily seen that I have produced such a device as substantially fulfills the objects of the invention as set forth herein.

While this specification sets forth in detail the present and preferred construction of 115 the device, still in practice such deviations from such detail may be resorted to as do not form a departure from the spirit of the invention, as defined by the appended claims.

Having thus described my invention what 120 I claim as new and useful and desire to secure by Letters Patent is:

1. A direction signal structure for vehicles comprising a movable signal arm, a stem movable in a slot, a cable leading from the stem, means between the cable and arm whereby with a movement of the stem the arm will be moved to a signal displaying position, and means tending to restore the arm to a neutral position whereby the cable is 125 130

5 maintained in tension; the slot having a side recess to receive the stem when the latter has moved a predetermined distance and the cable extending from the stem at an angle to that side of the slot in which the recess is located whereby to automatically pull the stem laterally into said recess when the stem is in alignment therewith.

10 2. A direction signal for vehicles including a movable signal arm, hand means for

moving said arm to a number of predetermined positions, and means connected to said hand means and adapted to be connected to the foot brake mechanism of the vehicle for independently moving said hand means and 15 arm to only one of said positions when the brake is applied.

In testimony whereof I affix my signature.

FREDERICK J. CASSARETTO.
